UNITED STATES PATENT OFFICE.

JOHN H. ALLDERTON, OF REDFIELD, SOUTH DAKOTA.

PORTABLE SIGNAL-FLAG.

1,197,424.

Specification of Letters Patent. Patented Sept. 5, 1916.

Application filed April 20, 1915. Serial No. 22,618.

To all whom it may concern:

Be it known that I, JOHN H. ALLDERTON, a citizen of the United States, residing at Redfield, in the county of Spink and State 5 of South Dakota, have invented certain new and useful Improvements in Portable Signal-Flags; and I do hereby declare the following to be a full, clear, and exact description of the invention, such as will enable others skilled in the art to which it 10 pertains to make and use the same.

The invention relates to a portable signal flag.

The object of the present invention is to 15 improve the construction of signal flags and to provide a portable signal flag adapted to be readily clamped to a track for protecting workmen on or about a train or a track where work is being done and capable of being 20 easily and quickly transferred from one point or place to another.

A further object of the invention is to provide a portable signal flag of this character of strong and durable construction 25 which will be both simple and inexpensive and which when set up properly in position cannot be accidentally blown down.

With these and other objects in view the invention consists in the construction and 30 novel combination and arrangement of parts hereinafter fully described, illustrated in the accompanying drawings and pointed out in the claim hereto appended, it being understood that various changes in the form, 35 proportion and minor details of construction may be resorted to without departing from the spirit or sacrificing any of the advantages of the invention.

In the drawing Figure 1 is a side elevation 40 of a portable signal flag constructed in accordance with this invention, Fig. 2 is an end elevation of the lower portion of the signal flag, Fig. 3 is a horizontal sectional view on the line 3—3 of Fig. 1.

45 Like numerals of reference designate corresponding parts in all the figures of the drawings.

In the accompanying drawing in which is illustrated the preferred embodiment of 50 the invention, 1 designates a staff or pole constructed of tubular metal such as gas pipe and having its lower portion flattened and provided with a lateral bend 2 for embracing one side of the head or ball 3 of a rail 55 4 which is embraced at the opposite side by a lateral bend 5 of a lever 6. The lever 6

which consists of a bar extends through slots or openings 7 in the staff or pole 1 and is pivoted at an intermediate point to the latter by a rivet 8 or other suitable fastening device which pierces the staff or pole and the lever. The staff or pole and the lever are provided at their lower ends with straight portions 9 and 10 to which are bolted, riveted or otherwise secured, jaws 11 60 and 12 which engage the web of the rail at the opposite faces thereof whereby the pole or staff is rigidly maintained in an upright position.

The jaws 11 and 12 are constructed of 70 sheet metal or other suitable material and are of a width substantially equal to the width or height of the rail and the lower edges 13 and 14 of the jaws are curved downwardly and outwardly to form flanges 75 to rest upon the bottom flanges of the rail. The lower arm of the lever is substantially straight above the lateral bend 5 and the upper arm is curved slightly and is reduced at the upper portion 16 and is adapted to be locked to the staff or pole by a slideable ring or loop 17 which is movable upwardly and downwardly on the staff or pole to engage with and disengage it from the lever 15. Any other suitable means, however, may be 80 employed for locking the lever in its closed or engaging position.

The staff or pole is equipped at its upper end with a signal flag 18 preferably constructed of sheet metal or other suitable material but a fabric flag may of course be 85 employed.

It will be seen that the portable signal flag is exceedingly simple and inexpensive in construction, that it possesses great 95 strength and durability and that it is adapted to be quickly applied to and removed from a rail. It will also be apparent that the clamping means firmly secures the staff or pole to a rail and that the signal 100 flag is rigidly maintained in an upright position and effectively prevented from accidentally blowing over.

What is claimed is:—

A portable signal including a vertical 105 staff extending upwardly from the head of a rail and provided near its lower end with a laterally extending bend passing around one side of the head of the rail, said staff being also provided below the bend 110 with an attaching portion, a lever pivoted intermediate of its ends to the vertical staff

and consisting of a straight lower arm provided at the lower portion with a bend extending around the opposite side of the head of the rail and having a lower attaching portion, and a curved upper arm adapted to fit at its upper end against the side of the staff, clamping plates secured to the attaching portions of the levers and fitting against the web of the rail and supported at their lower edges upon the bottom flanges of the rail, and a ring slidable on the staff and

arranged to engage over the upper end of the lever and limited in its downward movement by the curvature of the upper arm of the lever.

15

In testimony whereof I affix my signature in presence of two witnesses.

JOHN H. ALLDERTON.
